UNITED STATES PATENT OFFICE

RAYMOND F. MCNEAL, OF CHICAGO, ILLINOIS

FURNACE

Application filed April 8, 1932. Serial No. 603,977.

The present invention relates to furnaces and particularly to furnace constructions and has to do with the adaptation of a boiler for use with gun type fuel burners.

5 Experience has taught that when gun type fuel burners are installed in furnaces or fireboxes of boilers disintegration takes place because of the intense heat applied in such fireboxes and also the combusted fuel, impelled by pressure, often burns the headers and tube ends, thus necessitating early shutdown for extensive and expensive repair.

The present invention is directed to the provision of means whereby such objections 15 can be overcome and whereby gun type fuel burners can be safely and satisfactorily used with boilers without premature disintegration of the boiler fireboxes and with all increasing the efficiency of such boilers because 20 of such means.

Generally speaking, the invention contemplates a burner applied in an extension furnace wherein the fuel is combusted, and which extension furnace is surrounded by 25 water circulating pipes for cooling such extension and preheating the water. The pipes are protected by refractory material such as bricks or blocks so constructed and arranged as to enable ready removal of any blocks 30 requiring replacement and the ready installation of new blocks with minimum loss of time. The blocks are interlocked to prevent accidental displacement in service and 35 may be set up without mortar or similar binding agents.

An object of the present invention is to provide means whereby gun type fuel burners and other high temperature burners may 40 be used for boilers without causing disintegration or other damage to the boiler structure.

Another object of the invention is to provide a furnace extension which extension is 45 watercooled and which is disposed in direct communication with the boiler firebox.

A further object of the invention is to provide a furnace extension applicable to a boiler furnace or firebox for lengthening the path 50 of travel of the combustible fuel to prevent

excessive heat in the boiler firebox and thus eliminate damage to the furnace.

A still further object of the invention is to provide an auxiliary cylindrical combustion box having refractory lining and water 55 tubes in the lining for cooling the same.

A yet further object of the invention is to provide a furnace extension which is cylindrical and which has cooling pipes about its periphery and refractory interlocked blocks 60 surrounding said pipes and defining the cylindrical combustion chamber of said extension.

An important object of the invention resides in the provision of an extension furnace 65 which is generally cylindrical in shape and which is provided with embedded water flues which increase turbulence, afford higher furnace temperatures and generally achieve 70 higher boiler efficiency with a minimum of heat loss and without undue disintegration of the boiler or extension furnace structure.

A still further object is to provide a heat zone for high or low ratings, wherein circulating water carries off excessive heat and 75 prevents damage to the tiles or blocks embedding the water circulating means.

Another and yet further object of the invention is to provide novel interlocked bricks 80 or blocks for lining a cylindrical combustion chamber.

The above, other and further objects of the invention will be apparent from the following description, accompanying drawings 85 and appended claims.

The furnace extension herein illustrated and described is adaptable for oil, gas or powdered coal. However, the extension furnace may be readily employed for other kinds 90 of fuel.

The accompanying drawings illustrate embodiments of the present invention and the views thereof are as follows:

Figure 1 is a fragmental sectional view 95 of a fire tube boiler showing applied to the firebox thereof an extension furnace constructed according to and embodying the principles of the present invention.

Figure 2 is a vertical sectional view taken 100

substantially in the plane of line II—II of Figure 1.

Figure 3 is a fragmental sectional view through a boiler of the Scotch type showing applied thereto an oil burner extension embodying principles of the present invention and wherein two headers are used with such extension and connected at different points to the water space of the boiler.

10 Figure 4 is a vertical sectional view taken substantially in the plane of line IV—IV of Figure 3.

Referring first to Figures 1 and 2 it will be observed that a fire tube boiler designated generally at A is carried on the usual masonry setting designated at B. The boiler A has a combustion chamber, firebox, or furnace C into which open the ends of fire tubes 1. The ends of the tubes 1 are headed in the header 2 which is connected in the usual manner to the usual crown plate 3. The space within the boiler A is for water and is designated at D and includes, in the form illustrated in Figure 1, a rear water leg or water space 4 and a front water leg or water space 5.

25 The furnace extension, as illustrated in Figure 4, designated generally at E and as there illustrated includes a front header 6 which is of usual form and made as a ring.

30 The boiler A has an opening 7 to the firebox C of the same, with the water leg 5 surrounding such opening.

At intervals the header 6 has headed there-in tubes 8 arranged in cylindrical form about 35 the axis of the extension E with its tubes ex-tending rearwardly and headed into the wa-ter leg 5 of the boiler. The tubes extend axially of the extension, so that the exten-sion is substantially horizontally disposed.

40 The tubes are fashioned to form the outline of the extension, that is, the cylindrical out-line or shape of the same.

The outer or front end of the extension E is supported by feet 9 resting on concrete 45 piers 10, while the inner end is supported on legs or feet 11 resting on concrete piers 12.

The axis of the extension E extends in the same general direction as the length of the firebox C of the boiler A but the extension 50 is illustrated as inclined slightly to the hori-zontal.

The tubes 8 are surrounded by and em-bedded in refractory material which refrac-tory material defines a cylindrical combus-tion chamber F within the extension E.

60 The refractory material in the present in-stance is made up in the form of bricks or blocks wedge-shaped in radial section and sub-stantially rectangular in axial section as may be observed from Figures 1 and 2. Cer-tain of these blocks or bricks 13 are provided with recesses or notches 14 in similar sides thereof for surrounding portions of the sur-faces of the tubes 8 to afford refractory pro-tection for the portions of the tubes towards

the combustion chamber F. Interfitting or interlocking blocks 15 shown, in Figure 2, to be substantially wedge-shaped in transverse section are interposed between every two of the blocks 13 as may be observed from Fig-ure 2. If desired, a heat-insulating coating 16 may be applied about the outer ends of the several bricks or blocks. If desired, a metallic or other covering 17 may be applied about the insulation coating 16.

70 Against the front face of the header 6 are ring blocks 18 suitably applied and held in position, which blocks are of refractory ma-terial. These blocks rest on a centrally dis-posed ring 19 of refractory material which 75 forms the entrance opening to the combus-tion chamber F of the extension E. The insulating coating 16 may be applied over the front blocks 18 if desired, as shown at 80 19 in Figure 1.

A casing 20 is suitably attached to the front end of the extension E for receiving the oil burner set, designated generally at G. The oil burner set G, among other things, 85 includes a discharge nozzle and an oil supply pipe 21 and a pipe 22 communicating with a suitable source of fluid under pressure, such, for instance, as steam, for applying pressure to the oil to force the same into the combus-tion chamber F of the extension E. The usual 90 valve 23 is provided for regulating discharge of the steam into the combustion chamber F. Another valve 24 is provided in the steam line for further adjustment of the steam sup-ply.

95 As before stated, the inner ends of the wa-ter tubes 8 communicate with the front water leg or water space 5 of the boiler A so that boiler water is circulated through these tubes and through the header 6, being delivered to the header 6 by pipes 25 leading from the water leg 4 and communicating with the header 6. As the water becomes heated, which it does in its cooling of the extension E, the heated water will rise and return to 100 the boiler into the water legs 5, that is, from the inner ends of the extension.

105 It will be observed that the oil burner set G is of the gun fed type, that is, of the type which discharges the oil with considerable force. The provision of the oil burner exten-sion E allows the combustion of this oil to take place in the combustion chamber F of the extension which extension is watercooled, 110 with the combustion chamber walls of refrac-tory material, so that little, if any, damage is imparted to the extension because of the excessive heat present in the combustion zone of the oil burner. This combustible fuel, or 115 combusted fuel as it then becomes, passes into the firebox C of the boiler where it passes through the fire tubes 1 to the stack, thus heating the water in the boiler and evaporat-ing it. The circulation of the boiler water through the extension E preheats this water 120

to an extent where the vaporization of the warm water in and about and above the fire tubes 1 is hastened or expedited so that a boiler equipped with an oil burner extension 5 of the present invention makes steam faster and thus becomes more efficient in service.

Should it become necessary to replace or repair any of the bricks 13 or 15 forming the combustion chamber of the extension E, then 10 the covering 17 and the insulating covering 16 might be removed and the damaged bricks moved outwardly by pressure applied against the insides of the same. This is made possible by removing the key bricks 15 and then 15 the recessed bricks 13. New bricks may be installed by hooking the recesses or notches 14 of the bricks 13 about the tube 8 and then inserting the necessary key bricks 15 to firmly interlock all of the bricks together.

20 Referring to the forms illustrated in Figures 3 and 4, it will be observed that the arrangement is substantially the same as described with reference to Figures 1 and 2 except that the extension here designated E' is 25 slanted upwardly away from the front of the furnace 8 of the boiler K, the boiler illustrated in Figures 3 and 4 being of the Scotch type.

The boiler K of Figures 3 and 4 has an upper water space 26 and a lower water space 30 27, with the firebox or combustion chamber 8 defined by corrugated walls 28. The firebox H has a front opening 29 surrounded by masonry or cement 30.

35 The oil burner extension E' has a front header 31 and a rear header 32 which headers are connected at intervals by axially extending water tubes 33. The tubes 33 are arranged in a single series in cylindrical form parallel to the axis of the extension E'. 40 The header 31 is connected by pipes 34 with the water space 26 of the boiler, while the header 32 is connected by connections 37 to the water space 27 of the boiler. Water, therefore, circulates from the boiler, that is, 45 from the space 27 through the header 32, thence through the tubes 33 to the front header 31, thence returns to the water space 26 through the pipe 34, such circulation of boiler water cooling the extension E', at the 50 same time taking up some heat as to become preheated to a certain degree, thus hastening vaporization of the water within the boiler K.

55 The combustion chamber of the extension E' is designated at L and is cylindrical in shape. The cylindrical combustion chamber L is defined by refractory blocks or bricks 38 and 39 similar, respectively, to the blocks 13 and 15 of the extension E. The blocks 38 are provided with notches 40 for engaging the tubes 33 to protect the same from the combustion chamber L.

The bricks 38 and 39 may, if desired, be 65 covered by an insulating coating 41 spread

about the exterior of the same which, in turn, may be surrounded by a covering 42.

The extension E' is supported on front legs 43 rising from piers 44 in the foundation and rear legs 45 rising from piers 46 of the 70 foundation.

The front face of the front header 31 is covered by refractory slabs or blocks 47 supporting in place a central refractory ring 48 forming an entrance 49 to the combustion 75 chamber L of the extension. The blocks 47 are shown as covered by insulating material 50 which in turn is covered by a cover 51. An oil burner casing 52 is supported on the cover 51 with the oil burner set E arranged 80 to discharge through the opening 49 to the combustion chamber L of the extension E'.

The gun type fuel burner G delivers the fuel under pressure into the combustion chamber L where it is ignited and creates 85 a zone of maximum heat. The combusted fuel passes into the firebox H of the boiler K for heating the water there contained.

Inasmuch as the zone of maximum heat is within the refractory oil burner extension 90 E', no damage results to the combustion chamber H of the boiler K, even though the gun type of oil burner be utilized in connection with such boiler.

The bricks 39 and 38 of the extension E' are 95 placed in the same manner as described with reference to the bricks 13 and 15 of the extension E of Figures 1 and 2.

It will be observed that this invention provides an oil burner extension for application to boilers wherein the gun type of oil burners may be utilized without damaging the firebox of the boilers to any extent whatsoever. The zone of maximum heat is within the combustion chamber of the extension 100 the walls of which are of refractory material and watercooled, thus prolonging the life of such walls to a marked degree. The refractory wall structures of these extensions is such as to enable ready repair and replacement should any of the refractory material have to be replaced through wear due to long 105 service or through accidental breakage.

110 It will be observed that by the use of an oil burner extension of the character herein described, the combusted fuel under pressure is spent to some extent before the same enters the fireboxes of the boilers, thus relieving the fireboxes of the boilers from the intense heat generated in the zone of ignition 115 of the fuel.

The circulation of the boiler water through the extension has the double purpose of cooling the extension and of preheating the boiler water, thus not only efficiently cooling the refractory walls of the combustion chamber of the extension but preheating the boiler water to an extent whereby vaporization 120 thereof within the boiler is accelerated, thus 125

increasing the efficiency of the boiler and reducing the cost of fuel.

The circular arrangement of the furnace eliminates pockets and also eliminates losses of the influx of unconsumed combustible products, such as occur in square or semi-circular furnaces. It also furnishes complete circulation of the products of combustion. Furthermore, heat transference to the refractories is equally divided and in turn the heat from the refractories is reflected equally to the combustible matter.

The invention is not limited to oil burners because it is illustrated and described in connection therewith, as it is equally adaptable to other fuels, such as gas powdered coal, coke and the like, and also to stoker-fed boilers.

The water ring or header is an important part of the present invention in that it aids water circulation, thus enhancing the efficiency of the cooling of the extension and prolonging its life.

The term "brick" has been used herein generically, and not by way of limitation and is intended to include any refractory material suitable for such use, made in the form of blocks, tiles or bricks.

The invention has been described herein more or less precisely as to details, yet it is to be understood that the invention is not to be limited thereby as changes may be made in the arrangement and proportion of parts and equivalents may be substituted without departing from the spirit and scope of the invention.

The invention is claimed as follows:

1. A boiler arrangement including a boiler having a firebox, a cylindrical combustion chamber attached to said boiler and communicating with the front end of said firebox, a refractory lining for completely defining said cylindrical chamber, and water tubes embedded in said lining with every one of said tubes completely covered by said lining, said tubes communicating with the water spaces of said boiler for circulating boiler water through said lining to cool the same.

2. In combustion with a boiler having a firebox, a cylindrical combustion chamber communicating with said firebox, a plurality of axially extending water tubes disposed all around said combustion chamber, refractory material embedding all of said tubes and defining said cylindrical combustion chamber, every one of said tubes being completely surrounded by said lining, a header at one end of said chamber into which said tubes open, and means connecting said header and the other ends of said tubes with the water compartments of the boiler for circulating boiler water through the tubes of said combustion chamber to cool said chamber and heat the circulating water.

3. In a boiler arrangement, in combination

with a boiler having a firebox, a furnace extension communicating with said firebox and disposed against the front end of said firebox outwardly thereof, a header at one end of said extension, a plurality of water tubes communicating with said header and extending lengthwise of said extension and defining the periphery thereof, a plurality of refractory bricks embedding said tubes and completely surrounding every one of said tubes and defining the combustion chamber of said extension, and a fuel burner arranged for fuel discharge into said extension through the outer end thereof, said tubes being connected to the water spaces of said boiler for circulating boiler water through said tubes and header to cool said extension.

4. A boiler having a firebox, a furnace extension opening into said firebox, said extension having a cylindrical wall of refractory bricks, water tubes extending through said wall axially of said extension, headers at each end of said extension in communication with said tubes, and connections between said headers and different parts of the water space of the boiler for circulating boiler water through said headers and tubes for cooling said extension, all of said tubes being completely surrounded by the material of said wall with no part of any tube directly exposed to the interior of said chamber.

In testimony whereof I have hereunto subscribed my name at Chicago, Cook County, Illinois.

RAYMOND F. McNEAL.
